CLAIM

The ornamental design for a underwear, as shown and described.

DESCRIPTION

FIG. 1 is a front perspective view of a underwear of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading or hatching are not features of the design and are merely utilized to illustrate surface contours of the design in the drawings. The broken lines along the surfaces of the underwear depicts environmental feature lines that form no part of the claimed design.

1 Claim, 7 Drawing Sheets
